UNITED STATES PATENT OFFICE.

GEORGE WATKINSON, OF PHILADELPHIA, PENNSYLVANIA.

DESIGN FOR A RUBBER BOOT.

SPECIFICATION forming part of Design No. 33,991, dated January 29, 1901.

Application filed November 14, 1900. Serial No. 36,528. Term of patent 14 years.

To all whom it may concern:

Be it known that I, GEORGE WATKINSON, a citizen of the United States, residing at Philadelphia, in the county of Philadelphia and State of Pennsylvania, have invented and produced a new and original Design for a Rubber Boot, of which the following is a specification, reference being had to the accompanying drawing, forming part thereof, and in which is illustrated a side view of a boot embodying my design.

The leading feature of the design is the appearance (illustrated in the accompanying drawing) of gracefulness, strength, and uniqueness of the boot as a whole.

In the drawing, *b* indicates the counters, and *c* is the vamp, which has the relation illustrated in the drawing to the sole. The vamp and counters present a smooth appearance, and their union is accentuated by welt-like ornaments *e*.

a is the leg portion, and it also presents a smooth appearance.

The union of the leg, vamp, and counters is located above the ankle part *d* and is emphasized, in contrast with the smooth appearance of the vamp, counters, and leg, by a single welt-like ornament *ff'f²*, arranged in a smooth curve, substantially as shown.

Having described my invention, what I claim as new, and desire to secure by Letters Patent, is—

The design for a boot, substantially as described and shown.

In testimony whereof I have hereunto signed my name in the presence of two witnesses.

GEORGE WATKINSON.
